UNITED STATES PATENT OFFICE.

WILLIAM G. WIGHT, OF YALE, MICHIGAN, ASSIGNOR OF ONE-HALF TO HORACE E. BEARD, OF YALE, MICHIGAN.

SECTIONAL CONDUIT.

No. 909,354.

Specification of Letters Patent.

Patented Jan. 12, 1909.

Application filed January 11, 1903. Serial No. 410,423.

To all whom it may concern:

Be it known that I, WILLIAM G. WIGHT, a citizen of the United States of America, residing at Yale, in the county of St. Clair and State of Michigan, have invented certain new and useful Improvements in Sectional Conduits, of which the following is a specification, reference being had therein to the accompanying drawings.

10 The invention relates particularly to metallic sectional conduits, and consists primarily in means for connecting or joining the abutting sections.

15 It further consists in the peculiar construction of the connecting means, and still further in certain details of construction as will be hereinafter set forth.

20 In the drawings, Figure 1 is a perspective view of two abutting conduit sections, illustrating the connecting means; Fig. 2 is a vertical central section through the connected sections illustrated in Fig. 1; Fig. 3 is a view similar to Fig. 1, showing a modified form of connecting means; Fig. 4 is a view similar to 25 Fig. 1, showing a still further modification; and Fig. 5 is a vertical central section through the construction of conduit shown in Fig. 4.

With reference particularly to the construction of conduit shown in Fig. 1, A and B represent two abutting sections formed each of sheet metal, the meeting edges of which are riveted to form cylindrical sections. Each of these conduit sections is provided at 35 its meeting edge with a segmental flange, as C, in this instance a metal band extending preferably half way about the conduit section and riveted thereto. These bands are also provided with lateral offset portions at 40 their ends, indicated by the reference-letter D, which when the conduit sections are arranged in place register one with the other, and these registering portions are clamped by any suitable means, as bolts E. A conduit formed in this manner is especially 45 adapted for sewer work,—as a sewer pipe,—for the reason that the meeting ends of the conduit sections abut, and the interior of the conduit is of uniform diameter throughout 50 its length, there being no overlapping of the sections.

In Fig. 3 I have shown the conduit sections as made from corrugated metal and the

segmental flanges at the meeting ends of the sections F and G integral with the sections, 55 the latter being cut away at their ends for this purpose. I have also shown lateral offset portions H formed by angle-shaped pieces of metal riveted to the ends of the flanges, these offsets being adapted to register and to be clamped together in the same manner as those shown in Fig. 1.

In Fig. 4 a further modification of my improved conduit is shown, the section being formed preferably of corrugated metal and 65 the segmental flanges being integral. The conduit sections in this instance, however, are adapted to be brought into engagement in such a manner that each flange will overlap a segmental section or portion of the adjoining conduit section in the manner indicated in Fig. 5, producing a rigid construction of conduit. Any form of clamping means may be employed for holding the sections together, but I preferably use bands a 75 and b, with suitable band tighteners,—as for instance a turn-buckle c,—in each instance for clamping the band circumferentially about the conduit. These bands, as shown in Fig. 4, are adapted each to pass about the 80 body portion of one conduit section and circumferentially about the segmental flange of the adjoining section, thus tightly clamping the sections in place. This form of conduit is designed more particularly for culvert 85 work where the sections are of considerable size and a tight joint between the sections is not absolutely essential.

What I claim as my invention is,—

1. In a sectional metallic conduit, the 90 combination of abutting sections provided at their meeting ends with oppositely-disposed segmental flanges, and means extending circumferentially about the flanged ends of the conduit sections for holding the latter 95 together.

2. In a sectional metallic conduit, the combination of two abutting conduit sections provided each with a segmental flange, the flanges being oppositely disposed, and each overlapping a segmental portion of the adjoining section, and clamping means for the sections extending circumferentially about the flanged portions.

3. In a sectional conduit, the combination 105 of two abutting conduit sections formed of

2
corrugated metal and each provided with an integral segmental flange, the flanges being oppositely disposed and the sections assembled to bring the segmental flange of one section about a segmental portion of its abutting section, and clamping means for the sections consisting of bands and band-tighteners each extending circumferentially about

the flange of one section and the body portion of the adjoining section. 10

In testimony whereof I affix my signature in presence of two witnesses.

WILLIAM G. WIGHT.
